UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SHUTTLE-DRIVING MECHANISM FOR NARROW-WARE LOOMS.

Application filed April 11, 1927. Serial No. 182,987.

This invention relates to driving mechanism for looms designed for simultaneously weaving a plurality of strips of tape, ribbon and other narrow fabric.

- 5 In such looms it is customary to mount the shuttles permanently on the lay and to move all of the shuttles by positive actuating mechanism carried on the lay and partaking of the swinging movement thereof.
- 10 It is the general object of my invention to improve the driving connections to the shuttle operating mechanism on the lay, so that accurate timing may be more readily accomplished and so that the parts may be more 15 easily constructed and more readily accessible for adjustment or repairs. My invention further relates to arrangements and combinations of parts which will be herein-after described and more particularly pointed out in the appended claims.

A preferred form of the invention is shown in the drawings in which:

- Fig. 1 is a partial front elevation of a narrow ware loom, partly in section, and 25 showing my improvements embodied therein;

Fig. 2 is an end elevation, looking in the direction of the arrow 2 in Fig. 1;

Fig. 3 is a longitudinal sectional elevation, taken along the line 3—3 in Fig. 2;

- 30 Fig. 4 is a detail sectional end elevation, taken along the line 4—4 in Fig. 1;

Fig. 5 is a detail end view, partly in section, and taken along the line 5—5 in Fig. 1; and

- 35 Fig. 6 is a view similar to Fig. 5 but showing the parts in a different position.

Referring to the drawings, I have shown parts of a narrow ware loom of a commercial type, including a loom frame 10, and a 40 lay 11 mounted on swords 12 and 13 and pivoted to swing about suitable bearings fixed in the lower portion of the loom frame. The end sword 12 (Fig. 1) is preferably mounted on a sleeve 14, secured in the end 45 of the sword and extending through a bearing 15 supported on the loom frame 10.

The sleeve 14 is extended beyond the bearing end and is provided with a bracket 16 fixed on the outer end thereof and providing 50 a support for a pair of sprocket wheels 18 and 19, which are secured to each other and rotate together.

A chain 20 is secured to the larger sprocket wheel 19 and extends upward and around a

guide wheel 21 mounted in one end of the 55 lay 11. The upper end of the chain 20 is fastened to the end of a sliding rack bar 22, engaged by a series of pinions 23 by which the shuttles 24 (Fig. 2) are actuated.

A motor M is mounted on the loom and is 60 connected by a pinion 25 to a large gear 26 rotatable on a bearing shaft 27 and having a smaller gear 28 associated therewith. The gear 28 engages a large gear 29 (Fig. 2) 65 having a cross shaft 30 (Fig. 3) pivoted in a bearing of the web thereof.

A crank arm 31 is secured to one end of the cross shaft 30 and a gear 32 is secured to the other end and engages a gear 33 fixed 70 in position but concentric with the axis of the gear 29.

The gear 29 is mounted on a shaft 35 supported in fixed bearings 36 and 37 (Fig. 1). The crank arm 31 is provided with a crank pin 38 (Fig. 3) positioned in a long slot 39 75 in a lever arm 40. The arm 40 is provided with an elongated hub 41 loose on the shaft 35 and having a flange 42 at one end thereof.

A bevel gear 45 (Fig. 3) is mounted on a 80 hub or sleeve 46 loose on the shaft 35 and having a flange 47 engaging the flange 42 previously described. The flange 42 is provided with arcuate slots 48 and is connected to the flange 47 by a plurality of bolts 49.

With this construction the bevel gear 45 85 can be adjusted angularly with respect to the slotted lever arm 40, thus adjusting the timing of the shuttle motion.

The bevel gear 45 engages a bevel gear 50 (Fig. 4) at one end of a short shaft 51 supported in fixed bearings 52. A crank arm 53 is secured to the opposite end of the shaft 51 and is provided with a crank pin or roll 54 positioned in a slot or guideway 55 extending transversely in a diamond shaped sliding member 56 (Fig. 1) having bearings 57 90 slideable on a fixed shaft 58.

As the shaft 51 is rotated the crank pin 54 gives a reciprocating motion to the sliding member 56, and the planetary gearing provided in the driving connection to the shaft 51 causes the speed of this reciprocating movement to be greatly varied at different points in its cycle of movement. In fact the combination is such that at one point a pronounced dwell of the sliding member 56 100 is produced, although the driving gears 26, 28 and 29 are continuously rotated.

The sliding member 56 is provided with a lug 60 (Fig. 1) through which extends a threaded rod 61 secured by nuts 62 in said lug 60 and connected by turn buckles 63 and 64 to additional threaded rods 65 and 66. The rod 65 is connected by a chain 67 to the small sprocket 18 previously described, and the rod 66 is similarly connected at the opposite end of the loom.

10 The chain 67 extends through the sleeve 14 on which the lay is mounted and is thus positioned at the axis of movement of the lay, where it is not affected by the swinging motion of the lay.

15 The sliding member 56 is also provided with a lug 70 (Fig. 4) in its upper portion, which is offset to form a recess 71 for a guide bar 72 (Fig. 1), mounted on a bracket 73 fixed to the loom side 10. The guide bar 72 prevents angular movement of the sliding member 56 about the axis of the shaft 58, and holds the threaded rod 61 accurately in alignment with the axis of the bearing sleeve 14.

25 Having thus described my invention, it is believed that the operation and advantages thereof will be readily apparent. The driving mechanism herein described provides continuous rotation of the crank arm 31 about the axis of the cross shaft 30 and also about the axis of the gear shaft 35. This combination of motions provides an irregular rotating motion through the arm 40 to the bevel gear 45 and thence to the crank arm 53 which reciprocates the sliding member 56. The flanges 42 and 47 provide a convenient means for angularly adjusting the bevel gear 45 and thus varying the timing of the shuttle motion, and the connections from the sliding member 56 to the driving chains are conveniently located and readily accessible.

The entire construction has been found particularly effective in actual use.

45 Having thus described my invention and the advantages thereof, I do not wish to be limited to the details herein disclosed otherwise than as set forth in the claims, but

What I do claim is:—

50 1. In a narrow ware loom, a lay, bearings for said lay, a shuttle actuating rack on said lay, actuating mechanism for said rack, and

connections from said mechanism to said rack, substantial parts of which connections are disposed at and along the bearing axis of said lay and are longitudinally movable in alignment therewith, and said actuating mechanism including a sliding member to which said connections are attached in alignment with said axis, a shaft having an axis fixed in spaced relation to said lay axis, means to reciprocate said sliding member on said shaft, and means to prevent angular movement of said member.

2. The combination in a narrow ware loom as set forth in claim 1, in which said sliding member is of substantially diamond shape, with bearing lugs at the two sides thereof and a guide-way at the top thereof, said guide-way cooperating with a fixed guide bar to keep said member from turning on said fixed shaft.

3. The combination in a narrow ware loom as set forth in claim 1, in which said actuating mechanism includes a variable speed driving member, a crank arm engaging said sliding member, and means providing angular adjustment between said driving member and said crank arm.

4. The combination in a narrow ware loom as set forth in claim 1, in which said actuating means includes a crank arm continuously driven but at variable angular speed, a second crank arm engaging said sliding member, and a transmitting device between said two crank arms constructed to provide angular adjustment between said arms.

5. The combination in a narrow ware loom as set forth in claim 1, in which said actuating mechanism includes a crank arm engaging said sliding member, a bevel gear rotatable with said arm, a second bevel gear meshing with said first gear, a fixed shaft on which said second gear is loosely mounted, a sleeve on said shaft, means to give said sleeve an irregular oscillating movement, and a two-part flanged connection between said sleeve and said second bevel gear, the two parts of said flanged connection being angularly adjustable relative to each other.

In testimony whereof I have hereunto affixed my signature.

ELBRIDGE R. HOLMES.
